UNITED STATES PATENT OFFICE

94,219

DESIGN FOR A BUMPER PROTECTOR

Walter C. Jackson, Rahway, N. J., assignor to Tingley-Reliance Rubber Corporation, Rahway,
N. J., a corporation of New Jersey

Application July 24, 1934, Serial No. 52,676

Term of patent 7 years

To all whom it may concern:

Be it known that I, Walter C. Jackson, a citizen of the United States, residing at Rahway, in the county of Union and State of New Jersey, have invented a new, original, and ornamental Design for Bumper Protectors, of which the following is a specification, reference being had to the accompanying drawing, forming part thereof, wherein

I claim:

The ornamental design for a bumper protector,
as shown.
Signed at Rahway, New Jersey, this 9th day of July, 1934.

WALTER C. JACKSON.
